PENCIL HOLDER

David C. Feather, Portland, Oreg., assignor of forty per cent to James B. Pfouts, Portland, Oreg.

Application February 26, 1945, Serial No. 579,782

5 Claims. (Cl. 120—9)

This invention relates to pencil holders and is particularly adapted for the holding of short pencils.

The primary object of the invention is to provide a holder for using up short pencils, of which there are many thousands in existence.

A further object of the invention is to provide a holder for encasing the pencil completely while not in use, thereby protecting the point from breakage and also providing protection to the person carrying the pencil.

A still further object of the invention is the provision of an ornamental and convenient holder that can be carried in the pocket or purse of the user and be ready for instantaneous use.

Another object of the invention is the provision of a holder that is simple of construction, easy to manipulate to writing position or vice versa to inactive position by the user.

And another object of my new and improved pencil holder is to protect the user of the pencil from indelible pencils and the like while carrying the same.

These and other incidental objects will be apparent in the drawing, specifications and claims.

Referring to the drawing:

Figure 1 is a side view of my new and improved pencil holder, showing the pencil stored therein in inoperative position.

Figure 2 is a longitudinal sectional view of the holder, illustrating the pencil in writing position.

Figure 3 is a sectional view, taken on line 3—3 looking in the direction indicated, illustrating the method of locking the pencil in a fixed position.

Figure 4 is a side view of my new and improved holder showing the pencil being inserted, parts broken away for convenience of illustration.

In the drawing:

My new and improved holder consists of two parts or casings 1 and 2 movably interlocked at 3. The cap 2 has an extension 4 extending into the socket 5 of the cap 1, best illustrated in Figures 2 and 3. Where these two parts inter-lock they have a close but working fit so that they can be moved relative to each other with a slight friction. Within the extension 4 of the cap 2 is an offset opening 6. This opening is offset from the longitudinal center line of the cap, the purpose of which will be described later.

Below and adjacent the extension the portion 5 of the cap 1 is an offset opening or hole 7. This opening is offset from the longitudinal center line of the cap 1. At the lower end of the

cap 1 is an opening 8, which permits the point 9 of the pencil 10 to pass through.

I will now describe the operation of my new and improved pencil holder. The caps are separated and the pencil inserted therein, as illustrated in Figure 4, wherein the eccentric openings 6 and 7 are in alignment permitting the pencil to work freely within the holder. When the caps are brought together they are revolved relative to one another until the eccentric holes 6 and 7 are brought to the position as illustrated in Figures 2 and 3 wherein they are offset from one another. The eccentric hole 6 bears against the pencil at 11 and the eccentric hole 7 bears against the pencil at 12, while the point 9 is held in alignment by the opening 8 of the cap 1 as the eccentric holes 6 and 7 are tightened to holding position.

When it is desired to move the pencil within the holder, as illustrated in Figure 1, the caps are revolved relative to one another causing the eccentric 6 and 7 to release the pencil so that it can return to its position within the holder, after which the caps are again revolved relative to each other until the eccentric holes 6 and 7 bind the pencil as illustrated in Figure 1.

By the use of my new and improved holder a modern and unique pencil holder is provided, for which there are many short pencils that can be used to an advantage and there is a special advantage of my holder for the holding of indelible pencils and the like and for holding breakable pencils, such as chalks.

I preferably construct my new and improved pencil holder of an ornamental and transparent material, such as plastic or the like.

I do not wish to be limited to the exact design as illustrated, as other mechanical equivalents may be used still coming within the scope of my claims.

What is claimed as new is:

1. A pencil holder comprising two separable elements of hollow formation within which the pencil is placed, one of the elements being formed with an opening for the projection of the pencil point, the elements being interiorly formed to grip the pencil under relative rotation of the elements to hold it in any predetermined position within the holder.

2. A pencil holder comprising two separable elements of hollow formation within which the pencil is placed, one of the elements being formed with an opening for the projection of the pencil point, one of the elements being interiorly formed to provide an eccentric gripping portion, the

other of the elements being formed with a longitudinal offset gripping portion, the rotation of the elements moving the respective gripping portions in such relative positions as to grip the contained pencil.

3. A pencil holder comprising two separable elements of hollow formation within which the pencil is placed, one of the elements being formed with an opening for the projection of the pencil point, one of the elements being interiorly cut away to form a transverse eccentric portion, the other of the elements being cut away to form a second eccentric portion offset from the first eccentric portion whereby under relative rotation of the elements the eccentric portions may be moved to grip or free the pencil at will within the holder.

4. A construction as defined in claim 3 wherein the elements are mounted for longitudinally separating movement and for relative rotation

when connected, one of the elements being formed with an eccentric bearing portion adjacent the point of connection of the elements and the other of the elements being formed with an eccentric bearing portion below the point of connection of the elements.

5. A pencil holder consisting of two hollow caps, one of the caps overlapping the other when brought end to end, each cap having an offset eccentric hole therein through which a pencil passes, these eccentric holes are offset from the longitudinal center line of the caps when the caps are rotated relative to one another the eccentric holes grip the pencil passing therethrough, an opening is provided in the outer end of one of the caps for allowing the point of the pencil to extend through.
